UNITED STATES PATENT OFFICE

139,422

DESIGN FOR AN APPLIQUE INSIGNIA

Jesse Rafelman, Norfolk, Va.

Application August 25, 1944, Serial No. 115,030

Term of patent 14 years

(Cl. D3—9)

To all whom it may concern:

Be it known that I, Jesse Rafelman, a citizen of the United States of America, residing at Norfolk, in the county of Norfolk and State of Virginia, have invented a new, original, and ornamental Design for an Applique Insignia, of which the following is a specification, reference being had to the accompanying drawing, forming a part thereof.

In the drawing:

I claim:

The ornamental design for an applique insignia, as shown.

JESSE RAFELMAN.
